UNITED STATES PATENT OFFICE.

JOHN J. RIDGWAY, OF BROOKLYN, NEW YORK.

LOCK.

SPECIFICATION forming part of Letters Patent No. 542,777, dated July 16, 1895.

Application filed November 28, 1894. Serial No. 530,223. (No model.)

To all whom it may concern:

Be it known that I, JOHN J. RIDGWAY, a citizen of the United States, residing at Brooklyn, in the county of Kings and State of New York, have invented a new and useful Improvement in Locks, of which the following is a specification.

My present invention is designed as an improvement upon the lock shown and described in Letters Patent No. 513,279, granted to me January 23, 1894. In said Letters Patent the latch-bolt was operated by a knob from the inside of the door or by a key from the outside and was retracted into the lock-casing upon the release of the holding-tumbler and again projected by a spring after the opening of the door, the tumbler being held out of engagement, and when the door was thereafter shut the striking-plate retracted the latch-bolt a second time and released the tumbler, and as the spring again projected the latch-bolt the mechanism of the lock was operated, so that the door was securely locked by the engagement of the tumbler and could not thereafter be opened except by the knob from the inside or a key from the outside.

In my present invention the operation of the parts is identical with those just described, the object of the present invention being to simplify, compact, and strengthen the parts of the lock and to perfect the details of the operating mechanism.

In carrying out my invention I provide a cam-plate connected to the spindle and which is provided with a slot, and the latch-bolt is provided with a raised inner end against which the cam-plate acts directly, and the tumbler is provided with a pin which passes into the slot of the cam-plate, and the spring-tail is connected to and moves with the latch-bolt, so as to come beneath or above a nose on the tumbler as the same is swung by the cam-plate in the operation of the parts. This construction is less expensive to manufacture and the lock is simpler in its details and is stronger and more compact than the mechanism of my aforesaid patent.

In the drawings, Figure 1 is an elevation of the lock mechanism with the parts in the position they assume when locked with the latch-

bolt projection. Fig. 2 is a vertical cross-section of the same at the line xx of Fig. 1. Fig. 3 is an elevation similar to Fig. 1 with the parts in the position they assume when the latch-bolt is retracted by the operation of the key or knob. Fig. 4 is an elevation similar to Figs. 1 and 3 with the parts in the position they assume when the released latch-bolt is projected by its spring and the spring-tail engages the tumbler to keep the same out of contact with the latch-bolt, and Fig. 5 is a sectional plan at the line yy of Fig. 4.

The lock-case is to be of any desired construction and is usually made with top, bottom, back, and end plates and with a removable cap-plate or cover, and the latch-bolt a is provided as usual with a beveled end a' to enter the opening in the striking-plate upon the door-casing. The central portion of the latch-bolt is open for the passage of the spindle b , and this spindle b is operated by a knob b' upon the inside of the door or by a key mechanism from the outside of the door. The latch-bolt a is provided with a notch 2 on its lower edge and with a raised inner end a^2 , upon the upper part of which is a vertical face 4 and upon the lower part of which is a notch and adjacent to the notch a backward projection 3, in which is secured the spring-tail f' , and there is a corner stop 5 in the lock-case.

Connected to the spindle b is a cam-plate c having an upward projection c' and provided with a lower projection, in which is a slot 6 having two parts, the one at an angle to the other, and d is the spring for projecting the latch-bolt. The tumbler e is located beneath the cam-plate and is provided with a pivot 11 in the lock-case, and with a dog or head e' and a nose at the opposite end at 8, and with a projecting pin 7 passing through the slot 6 of the cam-plate c , and f is a spring connected to the lock-case for elevating the dog e' of the tumbler, so that it may engage the notch 2 of the latch-bolt. The lock-case is provided with a guide-block 12 above the latch-bolt and with a central hub 9, through which passes the spindle b of the cam-plate c .

In the position of the parts shown in Fig. 1 the latch-bolt a is projected and the parts are in the position they will occupy when the door

is locked, the beveled end a' being in the opening in the striking-plate. To open the door the knob b' is turned from the inside or a key mechanism from the outside to rotate the spindle b , and with it to turn the cam-plate c and bring the lower end of the cam-plate against the raised inner end a^2 of the latch-bolt and retract the latch-bolt into the case in the position shown in Fig. 3, the parts stopping against the corner stop 5 of the case. In this movement as the cam c is turned with the spindle its slot 6 operates the pin 7 to swing the tumbler e against the action of the spring f . This depresses the dog e' and removes the same from the notch 2 of the latch-bolt before the lower end of the cam-plate c comes in contact with the raised inner end a^2 of the latch-bolt, and as the cam gradually forces back the latch-bolt the tumbler is turned further until its back end or nose 8 is elevated above the line of the spring-tail f' . In this position the movement is completed and the door is open, after which the parts are presumed to be released, and when released the spring d projects the latch-bolt a , and in so doing turns the cam c and spindle, and the action of the slot 6 is to partially turn the tumbler e and to bring its nose 8 down upon the spring-tail f' , or, in other words, the spring-tail underrides the nose 8 and supports the tumbler in this position, so that the dog e' is kept out of the notch 2 of the latch-bolt. This position is shown in Fig. 4. If now the door is slammed to or otherwise shut, the striking-plate acts upon the beveled end a of the latch-bolt and retracts the latch-bolt into the case. This movement simply affects the latch-bolt and its raised inner end a^2 , the spring-tail f' , and the spring d , but does not necessarily move the spindle or cam-plate. This backward movement carries the spring-tail clear of the nose 8, so that the spring f is free to act and swing the tumbler e and carry its dog e' up against the under edge of the latch-bolt. As the door shuts, the spring d again projects the latch-bolt, and as projected the dog e' enters the notch 2 and the parts are locked, and the latch-bolt cannot be again operated or retracted except by the knob b' from the inside or a key mechanism from the outside, in the manner hereinbefore described. This locked position is shown in Fig. 1, wherein the upper vertical face 4 comes against the vertical face of the upward pro-

jection c' and the stability of the parts is more perfectly assured.

I claim as my invention—

1. The combination with a spring latch bolt and its tumbler, of a cam plate for acting upon and retracting the bolt and having a slot, means for turning the cam plate, a pin upon the tumbler operating in said slot for disconnecting and swinging the tumbler before the movement of the bolt, means connected to and moving with the latch bolt for holding the tumbler out of engagement with the latch bolt when the same is again projected and which means release the tumbler when the bolt is again retracted so that the tumbler may engage the latch bolt upon its second projection and lock the parts, substantially as set forth. 70

2. The combination with a spring latch bolt having a raised inner end, a notch 2 and a spring tail connected therewith, of a spring actuated tumbler having a dog or head at one end and a nose at the other end over-riding or under-riding the spring tail of the latch bolt, a spindle and means for operating the same, and means connected with the spindle and engaging the tumbler to operate the same 75 and the spring latch bolt, substantially in the manner and for the purposes set forth.

3. The combination with the spring latch bolt a its raised inner end a^2 and the spring tail f' connected therewith and a notch 2 in its lower edge, of the spring actuated tumbler e having a dog or head e' at one end to engage the notch 2 and a nose 8 at the other end, and a pin 7 adjacent to the nose 8, the spindle b , the cam plate c connected therewith and having a curved slot 6 in its lower portion receiving the pin 7 of the tumbler e whereby with the movement of the spindle and the cam the tumbler is disengaged therefrom and turned to bring its back end above the spring tail 95 and the latch bolt is simultaneously retracted said tumbler being kept out of engagement with the latch bolt when projected and is released when said latch bolt is again retracted so as to engage the latch bolt at its second projection, substantially as set forth. 100

Signed by me this 19th day of November, A. D. 1894.

JNO. J. RIDGWAY.
